UNITED STATES PATENT OFFICE

SIMON COOPER, OF BROOKLYN, NEW YORK

ELECTRICAL SOSTENUTO PIANO

Application filed March 25, 1927. Serial No. 178,208.

This invention relates to electrical sostenuto pianos of the type wherein a pulsator is provided for current fluctuation in such accord with the movement of the piano string during the vibration of the latter, that a magnet in circuit with said pulsator is operated to sustain the vibration of the string by magnetic pluck relative to the string during each vibratory movement of the string toward the magnet.

I have discovered that true sostenuto is apparently most closely obtained when the magnetic-pluck sustentation of the string vibration is initiated after the string vibration, following the sounding of the fundamental note by the hammer blow, is changed to have a loop formation which commences the sounding of the desired partials.

Therefore, one of the important objects of the invention is to provide a pulsator and mounting means for the latter, as well also as a method of operating such pulsator, adapted to insure such initiation of the magnetic-pluck sustentation of the string vibration; the invention being preferably carried out in this regard by depending at least partially on the mechanical vibration of a non-singing part of the string, say that part of the string beyond a bridge-piece, and preferably between the open agraffe and the bearing-bar, for operating the pulsator for current fluctuation.

It is well-known that an electro-magnet can be caused to alter its field of force much more smoothly by undulatory current flow rather than by actual make-and-break of the circuit, which latter emphasizes the self-induction and re-actance of the coils of the electro-magnet, and also the impedance due to the hysteresis of the iron in the magnet core. In varying the magnetic field sufficiently fast to synchronize with the movement of vibration of the string, every element for causing non-synchronism, as above, must be considered. In my co-pending applications Ser. Nos. 178,204, and others, filed March 25, 1927, I have disclosed and claimed several forms of current controllers or pulsators which cause undulatory flow of current, and these pulsators are so constructed as to have no inherent

period of vibration to interfere with the synchronous current wave for varying the magnetic attraction. Nevertheless, there are other elements which may have periodic vibration and which are necessary for co-ordinating the current controller with the vibrating string, and the avoidance of any exterior or foreign vibrations in the pulsator from these elements is one of the important objects of the present invention.

Another object of the invention, then, is to provide a pulsator mount so embodied that there will be avoided any exterior or foreign vibrations, such, for instance, as would result from the inherent pitch of vibration of a part of the pulsator mount.

As the invention is preferably carried out in this latter regard, said mount includes the features of a support for a pulsator electrode connected to a part of the piano which is usually designed to have no disturbing natural pitch of vibration, such as the bearing-bar, this support incorporating or associated with a connection, preferably also somewhat rigid, directly mechanically joining a pulsator electrode and a non-singing part of the string.

Another object is to provide a method of and apparatus for mounting a pulsator, especially in operative relation to a non-singing part of a string, in such manner that the current fluctuations set up in the pulsator and the field fluctuations set up in the magnet are, certainly so far as the trained musical ear can detect, pure and unadulterated duplicates, in amplitude and frequency, and in wave form and relation, of the vibrations of the string, that is, unaffected by any natural or inherent vibrations of a part or parts of the pulsator or its mount or of a part or parts of the piano itself.

A further object of the present invention is to provide a mount having the operative advantages just noted, and wherein, as may be desirable in some cases, only one of the electrodes of the pulsator is connected directly to a part of the mount.

Various other objects and advantages of the invention will be specifically pointed out or apparent hereinafter, in the course of a

description of various preferred of the many possible forms of the invention as shown in the accompanying drawings; it being understood, of course, that such forms are merely illustrative of combinations and arrangements of parts calculated to attain the objects of the invention, pursuant to present preference, and hence the detailed description of such forms now to be given is not to be taken as at all defining or limiting the invention itself. That is to say, the scope of protection contemplated is to be taken solely from the appended claims, interpreted as broadly as is consistent with the prior art, and with explanatory references to the specification only where a claim is ambiguous or to be impliedly limited beyond its express terms to avoid such art in order to save the validity of said claim.

In the accompanying drawings:

Fig. 1 is a diagrammatic view illustrating, together with one form of pulsator and circuit, one form of mount according to the invention;

Fig. 2 is an enlarged detail view of certain of the parts as seen in Fig. 1, but with the pulsator shown in axial section;

Fig. 3 is a view similar to Fig. 1, showing another form of the invention;

Fig. 4 is an enlarged view in side elevation of certain of the parts shown in Fig. 3, but showing a modification of the mount illustrated in Fig. 4; and

Fig. 5 is a view similar to Fig. 4, but showing still another modification of such mount.

Referring to all the views, a piano string is indicated at 10, stretched over the bridge pieces 11 and 12.

Said string after passing over the open 40 agraffe 11a traverses the open space 9 to the tuning pin 8; the length 10a of the string constituting a non-singing part of the string.

The electromagnet for vibrating the string by magnetic pluck is indicated at 13, and 45 14 indicates the pulsator for controlling said magnet, said pulsator being located in a circuit with the magnet, which circuit includes a suitable source of energy 15 and a switch 16 operated by the piano key 17 when the 50 latter is depressed.

The hammer for the string is conventionally indicated at H, and the bearing-bar at B.

The pulsator 14 is connected to that part 55 of the length 10a of the string which extends between the agraffe 11a and the bearing-bar B.

The only vibration this portion of the string can have is a very minute one, due to the flexure of the string when the main portion thereof between the bridges 11 and 12 60 is vibrating. The string vibrates in a plane at right angles to that of the sounding-board; and the length 10a of the string moves similarly. I have found that this latter movement is sufficient to cause differences in the 65 conductivity of the pulsator 14 well adapted

to control the action of magnet 13 to give true sostenuto.

The pulsator of Figs. 1 and 2, in the present case, includes a pair of coacting electrodes 18 and 19, which may be of squat cylindrical shape, spaced to form a chamber between their opposing faces for a collection 20 of granular carbonaceous material or the like, a cylindrical sleeve or tube 25 of fibre, felt or the like, being applied to hold together the other pulsator parts already referred to.

Here, control of the magnet for true sostenuto is a function of a direct mechanical connection between the string and one of the electrodes, as the connection 26. In the form of the invention shown in Figs. 1 and 2, further, there is a direct mechanical connection between the other electrode and the bearing-bar, as the connection 27; which latter connection acts, in combination with the other parts, to prevent the setting up of appreciable inherent periodic vibration in the pulsator and its mount of a nature to disturb the natural vibration of the string 10.

Said connection 26 is a somewhat rigid strip having an upbent end screwed to the electrode 19, as shown, and its other end suitably secured to or resting on the string along the length 10a thereof between bridge 11 and bar B.

Said connection 27 is a relatively very rigid support or bracket. This bracket is fastened to the bearing-bar B and has a down-turned length which suspends the outer portion of the pulsator, being clamped to the electrode 18 by means of a threaded stud 28 set in said electrode and carrying adjusting nuts 29 and 30.

After the pulsator is properly located, the nuts 29 and 30 permit of adjusting the electrode 18 to obtain the proper conductivity through the collection 20, and still permit vibratory movement of the electrode 19 as impulses are transmitted through connection 26.

Therefore, any movement imparted to the electrode 19 through the connection 26 will cause a compacting of the granular contents of the pulsator and cause a change in the conductivity of same; the outer electrode 18 being so held by the bracket 27 as to prevent any definite motion of said electrode.

To avoid short-circuiting the pulsator 14, connection 26 or bracket 27 is desirably of non-conducting material.

Referring to the form of the invention shown in Figs. 3, 4 and 5, this shows, first, that a different pulsator from that of Fig. 1, and also a different mount from that of Fig. 1, may be employed pursuant to the invention. A pulsator 14a rests or is secured in any ordinary or convenient way on a suitable bar or plate marked 22x in Fig. 3, 22y in Fig. 4 and 22z in Fig. 5. Near the inner end 125 of such plate in each case, the same is clamped,

wedged or otherwise straddled about or rested on the string between the agraffe 11a and bearing-bar B. The pulsator comprises in each instance a pair of cooperating electrodes with an interposed mass of carbon granules or the like, as is shown in detail in my co-pending application Serial No. 178,204, March 25, 1927. One of these electrodes is rigidly connected with a piano string by means shown, such means including the plate which is fastened to the piano string, and which has secured thereto a sleeve of fiber or the like in which the electrode is affixed. The companion electrode is loosely contained in an envelope of felt, wool, yarn or the like which fits inside the sleeve as to hold the electrode in proper relationship to the granular mass, a wrapping of yarn being provided to hold the outer portion of the envelope to the supporting bar, and a pad of felt being interposed beneath the other end of the pad and envelope as a further cushion medium.

The non-resonant electrode is relatively heavy; in other words, is of sufficient mass to give it such inertia that it will operate in effect as an "anvil" for the lighter directly actuated hammer, and being supported as it is in a non-resonant envelope, its motion relative to the other electrode, is slight and of less frequency.

In each of the variations of the form of mount shown in Figs. 3, 4 and 5, a strut 23 is secured at its inner end to the bearing-bar and near its outer end suspends a thread or wire 24 which is fastened to the plate 22x, 22y or 22z near its outer end, for instance as indicated at 24a, where the wire 24 is drawn through a hole in the plate and knotted below such hole.

In Fig. 3, the main mount or plate 22x is shaped as indicated at 22a, so it may be adjusted to impinge as shown against the bearing-bar.

In Fig. 4, the main mount or plate 22y is straight and clamps the string 10 so that the inner end 22b of such main mount may impinge upon the pin-plate 38.

In Fig. 5, the main mount or plate 22z is also straight, but is so shaped, as by properly shaping an end fork-wedge, as to be adjustable for impingement against the agraffe backing 11b.

In installation, after the main mount 22x, 22y or 22z is clamped to the string 10, the thread 24 is tautened until the main mount makes contact with the lower edge of the bearing-bar B, as in Fig. 3, or impinges upon the agraffe backing, as in Fig. 5. In Fig. 4, the thread is not relied on to secure impingement of the main mount against the pin-plate 20; and, instead, proper clamping of the main mount on the string is relied on for such impingement.

It will be noted that in the variations of Figs. 3, 4 and 5, each plate or main mount

22x, 22y or 22z has what can be termed a three-point suspension, in the sense that this supporting member has contacts with the bridge piece, and string, and is supported at its farther end as by the cord 24; and this three-point suspension, I have so far found, acts apparently as the ideal arrangement for eliminating or dulling any tendency in any part and particularly in the main mount to vibrate according to its own natural or inherent period; while, at the same time, although the motion imparted to the pulsator is very minute, because imparted from a non-singing part of the string, I find that adequate and full-volume sostenuto is obtained.

It will be further noted that the modifications of Figs. 3, 4 and 5 differ from the form of the invention shown in Figs. 1 and 2; in that in Figs. 3, 4 and 5, there is no direct mechanical connection from either electrode to any portion of the string 10. The electrodes in this case act by inertia to produce the current variations.

Inasmuch as many changes could be made in the above constructions, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language contained in the following claims are intended to cover all the generic and specific features of the invention herein described and all statements of the scope of the invention which, as a matter of language, might be said to fall therebetween.

What I claim is:

1. In an electric sostenuto piano, the combination of a string, a pulsator, a magnet in circuit with and actuated by said pulsator to sustain the vibration of a string, means for imparting vibrations to the pulsator from vibrations of the string, and means for excluding from the pulsator such other vibrations as will, to an extent audibly appreciable, interfere with true sostenuto.

2. In an electric sostenuto piano, the combination of a string, a pulsator, a magnet in circuit with and actuated by said pulsator to sustain the vibration of a string, means for imparting vibrations to the pulsator from vibrations of the string, a device for starting the string to vibrate first to sound the fundamental and then the fundamental and the partials, and means for insuring that magnetic sustentation of the string vibration will be initiated after such partials have begun to be sounded.

3. The piano defined in claim 1, wherein the last-mentioned means includes a suspension for the pulsator incorporating a fixed

bracket and a connection vibrating with the string.

4. The piano defined in claim 1, wherein the last-mentioned means includes a suspension for the pulsator incorporating a comparatively rigid bracket fixed to a part of the piano free of a period of vibration appreciably out of phase with that of the string, and a somewhat less rigid mechanical connection 10 vibrating with the string.

5. In an electric sostenuto piano, the combination of a string, a pulsator, a magnet in circuit with and actuated by said pulsator to sustain the vibration of a string, means 15 for imparting vibrations to the pulsator from vibrations of the string, while suspending the pulsator as a unit, and means for excluding from the pulsator such other vibrations as will, to an extent audibly appreciable, interfere with true sostenuto.

6. The method of obtaining sostenuto effects in an electrically vibrated piano string which consists in utilizing the non-singing part of the string for controlling the current 25 serving to cause vibration of the singing part of the string.

7. The method of obtaining sostenuto effects in a piano string having an electro-magnetic control for the vibrations of the 30 singing part of the string which consists in varying the electro-magnetic strength by means of the vibrations induced in the non-singing part of the string by the vibrations of the singing part of said string.

35. 8. The method of obtaining sostenuto effects in a piano string having an electro-magnet arranged to act on the singing part of the string as an armature which consists in alternately increasing and decreasing the 40 strength of the circuit through the magnet by utilizing the vibrations of the non-singing part of the string to effect changes in said current strength.

9. In a piano, a string, an electro-magnet 45 supported near said string to vibrate the same, a pulsator controlled by the vibration of said string and connected in series with the winding of said magnet, and a three point suspension of character defined for said 50 pulsator.

10. In a piano, a string, an electro-magnet supported near said string to vibrate the same, a pulsator controlled by the vibration of said string and connected in series with 55 the winding of said magnet, and a three point suspension of character defined for said pulsator, said piano having non-vibratile parts to which two points of the suspension are attached.

60. 11. In a piano, a string, an electro-magnet supported near said string to vibrate the same, a pulsator controlled by the vibration of said string and connected in series with 65 the winding of said magnet, and a three point suspension of character defined for said pul-

sator one of which is a point upon the string.

12. In a piano, a string, an electro-magnet supported near said string to vibrate the same, a pulsator controlled by the vibration of said string and connected in series with 70 the winding of said magnet, and a three point suspension of character defined for said pulsator one of which is a point upon a non-singing part of the string.

13. In a piano, a string, an electro-magnet 75 supported near said string to vibrate the same, a pulsator controlled by the vibration of said string and connected in series with the winding of said magnet, and a three point 80 suspension of character defined for said pulsator one of which is a point upon the string having a relatively minute amplitude of vibration as compared with another part of said string.

14. In a piano, a string, an electro-magnet 85 supported near said string to vibrate the same, a pulsator controlled by the vibration of said string and connected in series with the winding of said magnet, and a three point suspension of character defined for said pulsator, one member of said suspension consisting of a suspensory filament having a bearing point on the string.

15. In a piano, a string, an electro-magnet supported near said string to vibrate the 95 same, a pulsator controlled by the vibration of said string and connected in series with the winding of said magnet, a member attached to a fixed part of the piano, a mounting member for said pulsator including a 100 member bearing on said string and located beneath the last member, and a flexible filament connecting the free ends of said members.

16. In a piano, a string, an electro-magnet 105 supported near said string to vibrate the same, a pulsator controlled by the vibration of said string and connected in series with the winding of said magnet, a member attached to a fixed non-vibratile part of the 110 piano, a mounting member for said pulsator including a member bearing on said string and located beneath the last member, and a flexible filament connecting the free ends of said members.

17. In a piano, a string, an electro-magnet supported near said string to vibrate the same, a pulsator controlled by the vibration of said string and connected in series with the winding of said magnet, means to suspend 120 the pulsator from a part of the piano other than the string, and a brace extending from the pulsator to the string.

18. In a piano, a string, an electro-magnet supported near said string to vibrate the 125 same, a pulsator controlled by the vibration of said string and connected in series with the winding of said magnet, means to suspend the pulsator from a part of the piano other than the string, a brace extending from 130

the pulsator to the string, and a second brace extending from the pulsator to a part of the piano other than the string.

19. In a piano, a string, an electro-magnet supported near said string to vibrate the same, a pulsator controlled by the vibration of said string and connected in series with the winding of said magnet, means to suspend the pulsator from a part of the piano other than the string, and a brace extending from the pulsator to a bridge piece of the piano.

20. In a piano, a string, an electro-magnet supported near said string to vibrate the same, a pulsator controlled by the vibration of said string and connected in series with the winding of said magnet, and a three point suspension of character defined for said pulsator, one of said points being vibratile.

21. A sostenuto piano or similar instrument comprising in combination with the vibratory string, bridge, and bearing bar, a pulsator including two electrodes and comminuted conducting material between them, a direct connection from one electrode to a non-singing part of the string, and a non-resonant supporting member connected to the other electrode and to an adjacent fixed part of the piano structure.

22. A sostenuto piano or similar instrument comprising in combination with the vibratory string, bridge, and bearing bar, a pulsator including two electrodes and comminuted conducting material between them, an arm connected to one electrode and to a non-singing part of the string adjacent the bridge, and a supporting bracket connected to the bearing bar and to the other electrodes.

23. A sostenuto piano or similar instrument comprising in combination with the vibratory string, bridge, and bearing bar, a pulsator, a supporting member on which the pulsator is located and engaging the bearing bar and the string at a point near the bearing bar and between the latter and the bridge, an additional support connected to a stationary non-resonant part of the piano structure, and a flexible non-resonant connection therefrom to the first named support near its end remote from the string.

24. A sostenuto piano or similar instrument comprising in combination with the vibratory string, bridge, and bearing bar, a pulsator, a supporting member on which the pulsator is located and engaging the bearing bar and the string at a point near the bearing bar and between the latter and the bridge, an additional support connected to a stationary non-resonant part of the piano structure, and a thread-like element connecting the last named support to the first support at a point remote from the string.

25. A sostenuto piano or similar instrument comprising in combination with the vibratory string, bridge, and bearing bar, a pul-

sator, a supporting member on which the pulsator is located and engaging the bearing bar and the string at a point near the bearing bar and between the latter and the bridge, an additional support connected to the bearing bar, and a thread-like element connecting the last named support to the first support at a point remote from the string.

26. A sostenuto piano or similar instrument comprising in combination with the vibratory string, bridge, and bearing bar, a pulsator, a first support on which the pulsator is mounted and at one end engaging a non-singing part of the string adjacent the bridge and also at that end engaging a stationary non-resonant part of the piano structure adjacent the bridge, an auxiliary support connected to a stationary and non-resonant part of the piano structure adjacent the bridge, and a flexible non-resonant connection from said auxiliary support to the first support at a point near its end remote from the string.

27. A sostenuto piano or similar instrument comprising in combination with the vibratory string, bridge and bearing bar, a pulsator, a first support on which the pulsator is mounted and at one end engaging the string at a point adjacent the bridge and between the latter and the bearing bar and also at that end engaging the bridge, an auxiliary support connected at one end to the bearing bar, and a thread-like element connecting the auxiliary support to the first named support at a point near its end remote from the string.

28. A sostenuto piano or the like comprising in combination with the vibratory string, a pulsator including electrodes and comminuted conducting material between them, a connection from the string to the pulsator, and a non-synchronously-resonant supporting member connected to the pulsator and to an adjacent fixed part of the piano structure.

29. A sostenuto piano or similar instrument comprising in combination with the vibratory string, bridge, and bearing bar a pulsator including two electrodes and comminuted conducting material between them, a direct connection from one electrode to the string, and a non-synchronously-resonant supporting member connected to the other electrode and to an adjacent fixed part of the piano structure.

In testimony whereof I affix my signature.
SIMON COOPER.
